COMBINED BOX AND COVER THEREFOR

Earl S. Tupper, Smithfield, R. I.

Application May 23, 1955, Serial No. 36,147

Term of patent 14 years

(Cl. D58—11)

Fig. 1

I claim:

The ornamental design for a combined box and cover therefor, substantially as shown.
